UNITED STATES PATENT OFFICE.

FRED C. AREY, OF OAK PARK, ILLINOIS, ASSIGNOR TO NORTHWESTERN EXPANDED METAL COMPANY, OF CHICAGO, ILLINOIS, A CORPORATION OF ILLINOIS.

MACHINE FOR SLITTING SHEET-METAL STRIPS.

1,211,362.

Specification of Letters Patent.

Patented Jan. 2, 1917.

Application filed April 14, 1915. Serial No. 21,198.

To all whom it may concern:

Be it known that I, FRED C. AREY, a citizen of the United States, residing at Oak Park, county of Cook, State of Illinois, have invented a certain new and useful Improvement in Machines for Slitting Sheet-Metal Strips, and declare the following to be a full, clear, and exact description of the same, such as will enable others skilled in the art to which it pertains to make and use the same, reference being had to the accompanying drawings, which form a part of this specification.

The present invention relates to machinery for acting upon sheet metal in the process of forming expanded metal, such as expanded metal laths, and has for its object to produce a simple and efficient machine for slitting a panel extending lengthwise of a long narrow strip and lying usually between two unslotted margins, and delivering the strip in a proper condition to be received directly by other mechanism adapted to operate further upon it.

Viewed in its various aspects my invention may be regarded as comprising novel slitting rolls, as a novel feeding and guiding means for delivering a strip to the rolls, as a novel means for receiving a strip traveling at an angle to the direction of its length and shifting it so as to bring it parallel to the direction in which it is traveling or simply as a machine for working upon a strip and delivering it in a convenient position.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a top plan view of a portion of a machine arranged in accordance with my invention; Fig. 2 is a top plan view of so much of the machine which with the parts shown in Fig. 1 makes a complete machine; Fig. 3 is a side elevation of the portion of the machine shown in Fig. 1 on a larger scale, parts of the receiving table being broken away; Fig. 4 is a longitudinal vertical section taken at right angles to the axes of the slitting rolls and showing

the same portion of the machine as Fig. 3; Fig. 5 is a section taken approximately on line 5-5 of Fig. 4; Fig. 6 is a section taken approximately on line 6-6 of Fig. 4; Fig. 7 is a section taken approximately on line 7-7 of Fig. 3 with the upper slitting roller and its bearings removed and with the top bearing caps removed; Fig. 8 is a side view on an enlarged scale for receiving the slitted strip and bringing it parallel with the direction in which it is traveling; Fig. 9 is a longitudinal approximately central section through the device shown in Fig. 8; Fig. 10 is a view looking toward the left from the right hand end of Fig. 8; Fig. 11 is a section approximately on line 11-11 of Fig. 8; Fig. 12 is a section approximately on line 12-12 of Fig. 8; Fig. 13 is an axial section through one of the driving sprockets and adjusting means therefor forming part 75 of the strip feeding and guiding mechanism; Fig. 14 is a section taken approximately on line 14-14 of Fig. 13; Fig. 15 is a section taken approximately on line 15-15 of Fig. 2 on an enlarged scale; and Fig. 16 is a section taken approximately on line 16-16 of Fig. 2 on an enlarged scale.

The machine illustrated in the drawings is one designed to slit the central portion of a long narrow strip of metal, leaving unslotted margins at the sides, whereby when the unslotted margins are bent at right angles to the body of the strip and the slotted portion is expanded into a diamond mesh, the result is a metal lath unit which may be laid beside other units of the same kind and be permanently fastened thereto at its flanges so as to produce a sheet comprising an expanded metal surface backed at intervals by stiff ribs. In order to permit the central portion of a strip to be expanded while the side margins remain unexpanded, it is necessary to cut the slits at a slight angle to the direction of length of the strip instead of parallel with the direction of length as in the old Curtis process. Furthermore, the slotted panel is necessarily quite narrow where it is desired to have lath units of such a width that the reinforcing ribs will come close together, and therefore the ordinary slitting rolls cannot be employed.

In accordance with my invention, slitting by a rotary process is made possible by employing long slitting rolls each having a cutting surface or area limited to a nar-

row band extending about the corresponding roll in the form of a helix making with a plane at right angles to the axis of the roll an angle equal to the angle at which the slits are to be cut in the strip. The strips are fed between these rolls at the same angle to a plane at right angles to the axes of the rolls as that of the band-like cutting zones on the rolls, being properly positioned so as to cause the effective cutting band or belt to travel down the middle of the strip as the strip passes between the rolls. When the strip emerges from the slitting rolls it lies at an angle to the direction in which it is traveling and must therefore be straightened in order to bring it in a position to enter suitable expanding mechanism and therefore I have provided a receiving table so equipped that as each strip leaves the slitting rolls it is positively shifted so as to make it lie parallel with the direction in which it is traveling.

Reference being had to the drawings, 1 and 2 represent heavy cylindrical rolls each having at one end a stationary collar, 3, and at its other end a detachable collar, 4, in the form of a large nut. The space between the two collars on each roll is filled with disks or rather flat rings, 5, alternating the spacers, 6, of the same thickness as the disks or rings but of somewhat smaller diameter. The disks may be of the ordinary well known Curtis type having radial grooves, 7, extending inwardly from the periphery in the sides thereof, the edges of the disks between the grooves being cutting edges and the grooves permitting the portions of a strip or sheet coming opposite them in the slitting operation to remain unslitted. In order to secure the helical slitting zone the cutting rings or disks are mutilated, each having a section, 8, at its periphery, cut away and, beginning at either end of the roll, the disks are progressively offset relative to each other, the beginning of the mutilated portion of the cutting edge receding or advancing around the roll, depending upon which end is considered the starting end. The result is that the unmutilated portions of each roll form a sharply defined helical band extending around the roll from end to end.

As best shown in Fig. 4, the rings or disks are held against angular movement on the rolls by means of keys, 9, each of which enters a keyway in one of the rolls and one of a series of keyways, 10, in each of the rings or disks. The keyways are distributed along the entire inner edge of each of the cutting rings so that each ring may take any desired angular position upon the roll. The rolls are provided at their ends with suitable journals, 11 and 12; the journals for the upper roll extending into suitable bearing boxes, 13, 13, while the journals for the

lower roll extend into suitable journal boxes, 14 and 15. In the arrangement shown, the bearing boxes are mounted in suitable heavy pedestals, 16, supported at their lower ends upon a heavy base, 17. Beneath the bearing boxes, 14 and 15, are connected wedges, 18, between which and one of the pedestals is a screw device, 19, which may be turned to adjust the wedges in and out and thus raise and lower the bearing boxes 14 and 15 in order to secure accurate adjustment thereof. The rolls are removed by lifting them out through the top of the pedestals and, in order to make it unnecessary to lift the rolls to an undue height in this process, the portion, 20, of each of the pedestals just in front of the upper bearing boxes 13 is made separable, being preferably formed integral with the cap 21 which is hinged, as at 22, at the upper rear corners of the pedestals; this cap serving to tie the pedestals together, to hold the upper bearing boxes in place, and to lift out of the way the front upper halves of the pedestals when the cap is swung back.

The main driving shaft, 23, is mounted in and extends through the pedestals parallel with and behind the lower roll. On one end the driving shaft has a gear wheel, 24, meshing with a gear wheel, 25, on the journal 12 of the lower roll. On the opposite side of the machine there is on the driving shaft a gear wheel, 26, meshing with an intermediate gear wheel, 27, which in turn meshes with a gear wheel, 28, on the journal 12 of the upper roll; the gear wheels 26 and 27 being of the same size as the gear wheel 24; while the gear wheel 28 is the same size as the gear wheel 25, thus causing the two rolls to be driven in opposite directions and at the same speed when the driving shaft is set in motion.

In order that the slitting rolls may act properly on the strips it is necessary that the latter be fed to the rolls at the proper angle and in proper relation to the points at which the complementary cutters are in cutting relation to each other. In other words, if the strip is to have its central longitudinal panel slitted, the strip must be delivered to the rolls with its advance end meeting the rolls at one of the points where the cutting bands are in contact with each other, and at an angle to a plane at right angles to the axis of the rolls equal to the angle which the band-like cutting areas make with such plane. The width of the slitted panel in the strip is equal to the width of the slitting helices and, in order to bring this panel in the center of the strip, the advance end of the strip must be adjusted properly in the direction of the length of the rolls relative to the initial cutting elements which engage the strip. Therefore, in order to make the process commercially successful by combining rapidity with uniformity of product, it

is necessary to provide some means for automatically delivering a strip in such a position that it will be properly acted upon by the slitting rolls. This I accomplish by 5 means of a novel feeding table.

In advance of the rolls is a table, 30, having its top surface in the horizontal plane of the line of contact between the rolls, the table having a width equal at 10 least to the effective width of the rolls and having a length at least as great as the longest strip to be acted upon by the machine. Extending across the top of the table parallel with the axes of the rolls, and back 15 underneath the table are a series of endless chains, 31 to 36 inclusive. On one side of the table these chains pass over suitable idle running sprocket wheels, 37, while at the other side they run over driven sprocket 20 wheels, 38, mounted on a shaft, 39, extending lengthwise of the table and driven from the main driving shaft. In the arrangement shown, the main driving shaft drives a counter-shaft, 40, by means of suitable 25 spiral gearing, 41; the counter-shaft drives a second vertical counter-shaft, 42, by means of suitable spiral gearing including a spiral gear, 43; and the counter-shaft 42 drives the shaft 39 through suitable spiral gearing, 44. 30 The parts are so proportioned that the chains travel across the table at exactly the same speed as a point of contact between the two helical cutting areas travels in the direction of the length of the rolls as the 35 rolls are rotated. On the chains are suitable guides or abutments against which the edge of a strip, 50, lying upon the table and adapted to be fed between the rolls is adapted to bear, these abutments or guides being 40 so disposed that the strip will lie at the desired angle. Consequently, when the machine is in operation, the chains will hold the trailing end of the strip at the proper angle while it is passing through the machine and, by properly timing the chains, 45 the guides or abutments will serve to hold the strip in such a position that if it is simply slid along them and between the rolls, its advance end will be properly located with 50 reference to the cutting areas and the slits will be placed in the proper location in the strip.

The top of the table is preferably grooved as indicated at 51 along the lines of the 55 chains, thereby permitting the chains to lie below the upper surface of the table where they will not interfere with a strip resting on the table. The abutments or guides preferably take the form of rollers, 52, mounted 60 to revolve on journals projecting upwardly from the chains when they are at points above the table. The rollers are preferably flanged as indicated at 53, so that when the edge of a strip is pressed against them, any 65 tendency of the strip to rise will be over-

come and the strip will be held flat on the table. In order to locate the rollers accurately with respect to the top of the table, there is placed upon the trunnion beneath each of the rollers a guide plate, 54, which 70 enters guideways, 55, at the sides of the corresponding groove or slot, 51, and holds each roller against up and down movement as long as it is traveling across the top of the table. On the chains 33 to 36 there are only 75 single rollers while on the chains 31 and 32 there are double rollers that is, the rollers are arranged in pairs spaced apart a distance equal to the width of the strip to be operated upon. In this way the advance 80 end of the strip is positively held against transverse movement relative to the chains, insuring that the strip will not slip but will always be delivered accurately to the rolls and, as it is fed through the rolls, is positively held at the predetermined proper angle. Each chain may of course have more than one roller or set of rollers so that as soon as one strip has completed its passage through the slitting rolls there will be another strip ready to enter. 85

Since the chains must be accurately adjusted relative to each other and in definite time relation to the slitting rolls, I have provided means for permitting adjustments to 90 be made quickly and conveniently. Instead of fixing the sprocket wheels 38 to the shaft 39, I employ the arrangement shown in Figs. 13 and 14 wherein the sprockets are made readily adjustable on the shaft. Referring to these figures, 60 represents a collar fixed upon the shaft 39 beside one of the sprocket wheels 38, this sprocket wheel having on one side a hub provided with a worm wheel, 61. Extending around the hub and worm wheel is a housing, 62, provided with a sleeve or hub portion, 63, which is fixed to the shaft. Extending transversely through the housing is a worm, 64, meshing with the worm wheel 61. The worm and worm wheel 100 serve to lock the sprocket wheel to the shaft but, in order to adjust the sprocket wheel on the shaft, it is only necessary to turn the worm in the proper direction. The driving sprockets for all of the several chains are 105 alike so that each chain may be easily adjusted. However, after all of the chains have been adjusted individually so as to bring them into the proper relation one to the other, it is necessary to provide for adjusting all of the chains collectively so as to time them properly relative to the slitting rolls. This collective adjustment can conveniently be accomplished by permitting the shaft 39 to be turned independently of 110 the rolls. In the arrangement shown, I have provided somewhat the same adjustment between one of the driving gears for the shaft 39 and its shaft as that employed between the sprocket wheels 38 and the shaft 39. 115 120 125 130

Thus, the spiral gear wheel 43 is made loose on the shaft 40 and, keyed upon this shaft beside the spiral wheel is a worm wheel, 65, with which meshes a worm, 66, mounted in 5 suitable bearings, 67, on the side of the wheel 43. The worm and worm wheel lock the wheels 43 and 65, and therefore the wheel 43 and shaft 40, together; but, by turning the worm 66, the wheel 43 and all of 10 the parts driven thereby, including the shaft 39, are moved independently of the shaft 40. It will thus be seen that the individual chains are adjusted until a line drawn tangent to the rollers thereon makes the desired angle 15 relative to the longitudinal axis of the machine. A strip is then placed in position with its advance end extending into proximity to the rolls, and the chains are adjusted collectively so as to bring the end of the 20 strip into proper relation to the cutting helices; the parts being so arranged that just as the guide rollers on the chain 31 pass up to the top of the table and are in position to receive a strip, the slitting rollers are likewise in a position to receive and act upon a strip entering between them at the corresponding end.

It will be seen that the guide rollers come to the top of the table in the reverse order 25 of their distance from the slitting rolls so that long before the guide rollers on the chains 31 and 32 are in position to receive a strip, some of the other guide rollers will already have assumed their place on top of 30 the table and therefore the workman is able to lay a strip on the table and line it up nicely against two or more rollers before the rollers on the chain 32 come into the receiving position, and consequently he can slip 35 the advance end of the strip between the rollers on the chain 32 without loss of time when these rollers reach the receiving position. The same holds true with respect to the rollers on the chain 31, the strip being 40 however guided from both sides by the rollers on the chain 32 at the time the advance end is slipped between the rollers on the chain 31. A further push upon the strip causes its advance end to be introduced 45 between the slitting rolls which, cutting slits arranged at right angles to the axes of the rolls form in the strip a central panel of 50 slits, 68 (as best seen in Fig. 7) lying at the same angle to the longitudinal axis of the strip as the angle which the strip makes 55 with a plane at right angles to the axes of the slitting rolls. As the slitting rolls continue to revolve, the strip is fed forward at right angles to the axes of the rolls, the rolls 60 themselves acting as feeding devices, but because of the angular position of the strip, the line of contact between the strip and the rolls travels gradually from one end toward the other, following the line of contact between 65 the two helical cutting areas as they

roll upon each other from the point where the strip first entered between them. As the strip emerges from between the slitting rolls it lies at the same angle at which it lay upon the feed table and, in order that it may 70 properly enter a machine for further acting upon it, it is necessary that its position be shifted so as to bring its longitudinal axis parallel with the direction of travel. In the arrangement shown, I have arranged 75 a table, 70, in rear of the slitting rolls, this table having projecting through the top thereof a series of rollers, 71, suitably driven at the proper speed to carry the strip forward as fast as it is delivered from the slitting rolls. The rollers 71 may conveniently be driven from the counter-shaft 40 by means of another counter-shaft, 72, geared to the counter-shaft 40 by suitable gearing, 73, and in turn geared to the rollers 71 by 80 suitable spiral gearing, 74. Above one of the rollers 71 at some distance from the slitting rolls there may be a co-operating roller, 75, between which and the roller 71 the strip will be gripped and positively fed. Upon 85 the table, beyond the series of rollers 71 is what may be termed a tunnel, 80, having a widened mouth, 81, at the advance end and the interior contour of a warped surface, this contour being that which the buckling 90 strip will take when it is grasped at one end and pressure applied to swing it over parallel with its direction of movement. In the arrangement shown, the tunnel consists of 95 side walls, 82 and 83, and top and bottom 100 walls, 84 and 85. The mouth of the tunnel is of a height equal to the height of the side walls and of a width equal to somewhat more than half the width of the table. At its opposite end the width of the tunnel is 105 approximately equal to the width of a strip and of not much greater height, this portion of the tunnel lying adjacent to and parallel with the side of the table nearest which the advance end of the strip lies when it passes 110 through the slitting rolls. At a short distance within the mouth of the tunnel it contracts sharply in depth, the top falling and the bottom rising although both the top and the bottom are higher at their inner edges 115 than at their outer edges. Between what may be termed the entrance to the contracted portion of the tunnel, indicated at 120 86, and the outlet end of the tunnel indicated at 87, the tunnel rises in a gradual 125 curve as indicated at 88 and then sweeps down in a reverse curve to the outlet end. A strip being fed forward on the table 70 enters the flaring mouth of the tunnel and naturally follows the contour of the tunnel 130 as it is pushed forward and swung laterally and finally emerges lying parallel with the longitudinal axis of the machine. Where the machine herein illustrated is placed directly in advance of an expanding machine,

the advance end of the strip leaving the straightening tunnel will be grasped by the expanding mechanism so that the rear end of the strip will be drawn through the tunnel. However, any suitable means may be provided for carrying the rear end of the strip through the tunnel; the strip may be drawn through by hand or suitable feed rolls may be placed just beyond the tunnel.

10. While I have illustrated and described with particularity only a single preferred form of my invention, I do not desire to be limited to the exact structural details thus illustrated and described; but intend to 15 cover all forms and arrangements which come within the terms employed in the definitions of my invention constituting the appended claims.

I claim:

20. 1. In a machine of the character described, rolls having helical complementary cutting zones containing cutting edges lying in planes at right angles to the axes of the rolls, and means for feeding a strip to be operated 25 upon between the rolls at an angle to the planes of the said cutting edges.
2. In a machine of the character described, rolls having helical complementary cutting zones containing cutting edges lying in 30 planes at right angles to the axes of the rolls, means for feeding a strip to be operated upon between the rolls at an angle to the planes of the said cutting edges, and means for receiving the strip from the rolls and 35 shifting it so as to bring it parallel with the direction in which it travels.
3. In a machine of the character described, strip-working mechanism, means for feeding a strip to said mechanism at an acute angle 40 to the direction of length of the strip, and means for receiving said strip from said mechanism and shifting it so as to bring it parallel with the direction of movement thereof.
45. 4. In a machine of the character described, strip-working mechanism adapted to act on a strip passing through the same at an acute angle to the direction of the length of the strip, and means in advance of said mechanism for guiding the trailing end of a strip in said mechanism so as to maintain it at said angle to the direction of feed.
5. In a machine of the character described, strip-working mechanism adapted to act on 55 a strip passing through the same at an angle to the direction of the length of the strip, means in advance of said mechanism for guiding the trailing end of a strip in said mechanism so as to maintain it at said angle 60 to the direction of travel, and means for receiving said strip from said mechanism and shifting it so as to bring it parallel with the direction of travel.
6. In a machine of the character described, 65 strip-working mechanism adapted to act on

a strip passing through the same at an acute angle to the direction of its length, a feed table in advance of said mechanism, and means on said table and movable across the same in engagement with a strip, passing 70 through said mechanism so as to maintain the trailing end of the strip at the aforesaid angle.

7. In a machine of the character described, strip-working mechanism adapted to act on 75 a strip passing through the same at an acute angle to the direction of its length, a guide in advance of said mechanism for engaging with an edge of a strip passing through said mechanism, and means for moving said 80 guide transversely of the direction of forward travel of the strip at a rate sufficient to keep the guide in contact with the strip and hold the latter at the aforesaid angle.

8. In a machine of the character described, 85 coöperating rotary rolls each comprising a series of spaced co-axial disks fitting between and slightly overlapping the disks of the other series, the disks being complementary interrupted cutting edges adapted to 90 cut rows of spaced short slits in a strip passing therethrough, and the disks being mutilated so as to confine the cutting zones to helical bands extending around the rolls.

9. In a machine of the character described, 95 coöperating rotary rolls each comprising a series of spaced co-axial disks fitting between and slightly overlapping the disks of the other series, the disks being complementary interrupted cutting edges adapted to 100 cut rows of spaced short slits in a strip passing therethrough, the disks being mutilated so as to confine the cutting zones to helical bands extending around the rolls, and means for feeding between the rolls a strip lying 105 at an angle to the axes of the rolls corresponding to the angle of said bands.

10. In a machine of the character described, coöperating rotary rolls each comprising a series of spaced co-axial disks fitting between and slightly overlapping the disks of the other series, the disks being complementary interrupted cutting edges adapted 110 to cut rows of spaced short slits in a strip passing therethrough, the disks being mutilated so as to confine the cutting zones to 115 helical bands extending around the rolls, and transversely-movable guiding means for guiding a long narrow strip to be operated upon between the rolls at a point where the 120 complementary cutting edges are in cutting relation to each other and maintaining the trailing end of the strip at the proper angle to maintain the cutters in cutting relation to the strip as the strip passes through the 125 rolls.

11. In a machine of the character described, rotary rolls having complementary helical band-like cutting zones extending around the same and containing cutting co- 130

- operating edges lying in planes at right angles to the axes of the rolls, a guide in advance of the rolls, and means for moving the guide in the direction of the length of the rolls at the same speed that the line of contact between said zones travels lengthwise of the rolls.
12. In a machine of the character described, rotary rolls having complementary helical band-like cutting zones extending around the same and containing cutting co-operating edges lying in planes at right angles to the axes of the rolls, a guide in advance of the rolls, said guide having a guiding face lying at the same angle to a plane at right angles to the axes of the rolls as the angle which said cutting zones make with said plane, and means for moving the guide in the direction of the length of the rolls at the same speed that the line of contact between said zones travels lengthwise of the rolls.
13. In a machine of the character described, rotary rolls having complementary helical band-like cutting zones extending around the same and containing co-operating cutting edges lying in planes at right angles to the axes of said rolls, a guide in advance of said rolls, driving mechanism including a gearing between said rolls and said guide for causing the guide to move transversely of said planes when the rolls are rotated.
14. In a machine of the character described, rotary rolls having complementary helical band-like cutting zones extending around the same and containing co-operating cutting edges lying in planes at right angles to the axes of said rolls, a guide in advance of said rolls, driving mechanism including a gearing between said rolls and said guide for causing the guide to move transversely of said planes when the rolls are rotated, said gearing including means for shifting the guide to adjust the same without rotation of the rolls.
15. In a machine of the character described, strip-working mechanism adapted to act on a strip passing through the same at an angle to the direction of its length, a feed table in advance of said mechanism, endless belts extending across said table at intervals, devices on said belts for engaging with the edge of a strip, and means for operating said mechanism and said chains in unison with each other.
16. In a machine of the character described, strip-working mechanism adapted to act on a strip passing through the same at an angle to the direction of its length, a feed table in advance of said mechanism, endless belts extending across said table at intervals, devices on said belts for engaging with the edge of a strip, means for operating said mechanism and said chains in unison with each other, and means for shifting said belts independently of each other to adjust said devices so as to bring the strip at the desired angle.
17. In a machine of the character described, strip-working mechanism adapted to act on a strip passing through the same at an angle to the direction of its length, a feed table in advance of said mechanism, endless belts extending across said table at intervals, devices on said belts for engaging with the edge of a strip, means for operating said mechanism and said chains in unison with each other, and means for shifting said belts collectively with respect to said mechanism to vary the time relation between said devices on the belts and said mechanism.
18. In a machine of the character described, strip-working mechanism adapted to act on a strip passing through the same at an angle to the direction of its length, a feed table in advance of said mechanism, endless belts extending across said table at intervals, devices on said belts for engaging with the edge of a strip, means for operating said mechanism and said chains in unison with each other, means for shifting said belts independently of each other to adjust said devices so as to bring the strip at the desired angle, and means for shifting said belts collectively with respect to said mechanism to vary the time relation between said devices on the belts and said mechanism.
19. In a machine of the character described, strip-working mechanism adapted to act on a strip passing through the same at an angle to the direction of its length, a feed table in advance of said mechanism, said table having a series of transverse grooves in the top thereof, endless belts extending across the table through said grooves, projections on said chains adapted to extend above said grooves and engage with an edge of a strip on the table, and means for driving said mechanism and said belts in unison with each other.
20. In a machine of the character described, strip-working mechanism adapted to act on a strip passing through the same at an angle to the direction of its length, a feed table in advance of said mechanism, said table having a series of transverse grooves in the top thereof, endless belts extending across the table through said grooves, projections on said chains adapted to extend above said grooves and engage with an edge of a strip on the table, said projections being grouped in pairs spaced apart a distance equal to the width of said strip on the belts near the said mechanism and being arranged singly on the other belts, and means for driving said mechanism and said belts in unison with each other.
21. In a machine of the character described, strip-working mechanism, a feed

- table in advance of said mechanism, a shaft arranged along one side of said table, wheels distributed along the shaft, means for moving the wheels individually angularly upon the shaft, endless belts passing around said wheels and extending across the table, strip-engaging devices on said belts, and means for operating said mechanism and said shaft in unison with each other.
- 10 22. In a machine of the character described, strip-working mechanism, a feed table in advance of said mechanism, a shaft arranged along one side of said table, wheels distributed along the shaft, means for moving the wheels individually angularly upon the shaft, endless belts passing around said wheels and extending across the table, strip-engaging devices on said belts, means for operating said mechanism and said shaft in unison with each other, and means for turning said shaft independently of said mecha-
- nism in order to vary the time relation between said mechanism and said strip-engaging devices.
- 5 23. A slitting roll comprising a shaft, a series of disks arranged on said shaft side by side and spaced apart from each other, the disks being mutilated so as to place in relief from the remainder thereof portions forming a helical band around the roll. 25
- 15 24. A slitting roll comprising an elongated cylindrical support, disks of uniform thickness arranged on said support and spaced apart from each other a distance equal to their thickness, the edges of the 30 disks being cutting edges, and the disks being mutilated so as to confine the cutting portions to a helical band extending around the roll. 35
- 20 In testimony whereof, I sign this specifica- 40

FRED C. AREY.
